UNITED STATES PATENT OFFICE.

JAMES P. SCARTSARIS, OF JAMESTOWN, NEW YORK.

AUTOMATIC RAILWAY-SWITCH-OPERATING MECHANISM.

1,371,937.

Specification of Letters Patent. Patented Mar. 15, 1921.

Application filed September 15, 1920. Serial No. 410,385.

To all whom it may concern:

Be it known that I, JAMES P. SCARTSARIS, a citizen of Greece, residing at Jamestown, in the county of Chautauqua and State of 5 New York, have invented certain new and useful Improvements in Automatic Railway-Switch-Operating Mechanism, of which the following is a specification.

This invention relates to switch operating 10 mechanism and more specifically to that type which is operated from the cab or front of a railway car.

One of the objects of my invention is the provision of a switch operating mechanism 15 which may be simultaneously locked and unlocked when the switch is actuated.

Another object of my invention is directed to a novel and improved hand operated mechanism for positively actuating the 20 switch and its locking means to open or close the same as desired.

Another and very important object of my invention relates to a switch operated mechanism of the above class which will be simple in construction, highly efficient, and positive in operation, consisting of comparatively few parts which may easily be installed, and which will not likely get out of 25 order and otherwise embracing and combining to the essential safety requirements 30 of devices of this type.

With these objects in view and others which will be apparent as the description proceeds, the invention resides in the combination and arrangement of parts and in the details of construction hereinafter described and claimed, it being understood that within 35 the scope of what is claimed, changes in the precise embodiment of the invention can be 40 made without departing from the spirit and scope thereof and in which—

Figure 1 is a plan.

Fig. 2 a fragmentary side elevation of a frog and its locking mechanism.

45 Fig. 3 is a side elevation of one of the rock arms for actuating the switch.

Fig. 4 is a section on the line 4—4 of Fig. 1.

Fig. 5 is a front elevation, partly in section of the lever control mechanism.

Fig. 6 is a side elevation of the roller guide.

Numeral 1 designates a railroad track having the usual rails 2, 3, and numeral 4 designates a side track having rails 5, 6, 55 supported by the usual ties. The rails 5, 6,

leading to the main track are connected to the same by suitable mechanism now to be described.

Referring to Fig. 1 it may be seen that the main rails 2, 3, are split as at 8, 9, so that the said rails may support the switch points 10, 11, of the side track thrown into or out of engagement with the switch points 12, 13 of the main rails, it being of course, understood that the movable sections of the main and side track operate in suitable plates (not shown) in proximity to the switch proper. The switch points 10, 11, of the side track and the switch points 12, 13, of the main track are connected to each other by L-shaped longitudinally extending frogs 14, 15, and a transverse rod 16 extending beneath the rails as shown in Fig. 1 connecting all of said frogs. It will now be seen that as the frogs 14 and the switch points 10, 11 are thrown toward the main rails, the switch points 12, 13, and the frogs 15 thrown away from the main rails, the side track will be thrown open for travel. On the other hand when the longitudinal frogs 15 and switch points connected thereto are actuated the side track will be closed and the main track open for travel.

Positioned forwardly of said switch points, I have provided U-shaped guides 16^a, 17 secured by fastening elements 18, 19, to the rail flanges and slidably locking bolts 20, 21, having reduced ends 22 which are retained in their locked position in apertures 23 and the forward ends of the frogs above referred to and as clearly shown in Fig. 2.

It will be apparent that the locking members will securely hold the respective frogs and switch points in their locked position when the main track or side track are open for travel.

The forward ends of the locking bolts 20, 21, are provided with transverse pins 24 to which the eyes 25 of the forwardly extending connecting rods 27, 28, are fastened. The said connecting rods 27 are secured to upstanding lugs 27^a, 28^a of transverse rock shafts 29, 30, secured to certain ties 29^a, 30^a also shown in Fig. 1. The rock shaft 29, has its bent end 31 connected by a cable or pulley 32 passing over rollers 33, 34, to the frog 14 outside the rail 2 so that when the rock shaft is actuated it will throw the said frog in or out of engagement with the said rail and of course, operate the corresponding frog 15 on the in-

side of the rail and thereby open the side track for travel. The connecting rods 28 above referred to are likewise secured to transverse shaft 35 having upstanding lugs 35^a the said rock shafts also having a bent arm 36 which is however, on the opposite side of the track and is connected by a cable or pulley 37 passing over a pulley 39 connected to the frog 15 in a similar manner to the connection of the frog 14. Similarly as the rock shafts are actuated the frogs 14 will be thrown into or out of engagement and the main track will be open or closed.

The rock shaft 40 provided with a bent arm 40^a outside the main rail 3 is connected by pulley 41 and a second rock shaft 42 on the side track similarly provided with bent arms 42^a as the corresponding pulley 43 on the opposite side of the track to operate the respective frogs connected to the main and side tracks for operating the same when from the opposite direction. Referring now to Figs. 5 and 6, I have shown a preferred form of actuating mechanism operable from the inside or cab of an engine for operating the respective rock shaft 29, or 35 when it is desired to open or close the main or side track for travel.

Secured to the main rails, I have provided longitudinally extending roller guides 44, 45, in which the respective rock shafts are actuated being considerably outside the rails and side roller guides for engagement with a roller mechanism hereinafter to be described. The roller guides are positioned one in advance of the other and on opposite sides of the track. The lower flange 47 of the said guides is secured to the under side of the rails and have a vertically extending portion 45 terminating in a wide flange 45^a outside of and above the top of the rails, and said flange adapted to guide one of a pair of rollers hereinafter referred to. Suspended and carried to the body 48 of an engine cab (not shown) and equally spaced from the sides 49 thereof, are tubular members 50 supporting a transverse cross beam 51, having apertures 51^a. A slideable collar 52 in each of the said tubular members is provided with a transverse pin 53 supporting the roller carrying rod 54 extending through the apertures 51^a, the said rod carrying the pair of rollers 55, 55^a, the roller 55^a adapted to engage the flange 45^a of the roller guide, and the roller 55 to engage and actuate the bent arm 46 of the rock shaft.

Links 56 on each side of the collar 52 are also connected to the pin 53 passing through the upper end of the rod 54 and supporting the same within the tubular members. The said pins are slideable in recesses 57 of said tubular members, a spring 57^a being interposed between the collar 52 and bottom of the tubular member to normally retain the rod 54 and its rollers in an elevated, inop-

erative position. The links 56 above referred to are connected to laterally extending bearing arms 58 secured by pins 59 said arms 58 journaled in bearings 59 secured by fastening elements 59^a centrally of the cross beams 51 above referred to. The arms 58 are provided with friction rollers 60 supported by pins 61. An upwardly extending lever 62 passing through a recess 62^a and into the cab proper and having a right angled arm 63 for engagement with the friction rollers is adapted to actuate either of the members 58.

The lever 62 is journaled in central bearings 59^a and is provided with a release plunger 64 retained in the notch 65 and releasable therefrom so that the arm 63 may be reversed to actuate either of the arms 58 to operate the left or right hand rollers 55 and the rock shafts 49 or 35.

Assuming that the operator desires to travel on the side track, lever 62 is actuated to the left, depressing the left arm 58, rod 54 and rollers 55, 55^a, and as the engine advances the outer roller 55 will strike the upstanding bent arm 46 and thereby actuate the rock shaft 29. The opposite bent arm 31 of shaft 29 and its connected cable 32 will then actuate the frogs 15 as the sliding bolts 21 are simultaneously released from the frogs by the rods 27. As the frogs 15 are thrown outwardly and the frogs 14 thrown inwardly, the cables 37 connected to the bent arm 36 actuate the rock shaft 35 and the rods 28 to lock the bolts 20 in the frogs 14. When in this position it is desired to throw the frogs 14 outwardly, the operator will actuate the lever 62 and right arm 58, and its corresponding rollers, which will engage the guide 45 and bent arm 47 of the rock shaft 35. The bent arm 36 and its cable 37 will throw the frogs 14 outwardly, and as the locking bolts 20 are withdrawn the bolts 21 lock the frogs 15.

It will now be apparent from the above description that I have devised a very efficient, positive and practical switch, which may be operated by hand or from the cab of an engine, and which I have found to be highly satisfactory for the results described. It is thought that a switch operated mechanism constructed in accordance with my invention is particularly well adapted for its various uses on the old style as well on the new pattern of switches, by reason of the convenience and facility with which it may be assembled, installed and operated and it will be obvious that my invention is susceptible of various changes and modifications without departing from the principles and spirit thereof and therefore I do not wish to be understood as limiting myself to the precise arrangement and formation of the several parts shown in carrying out my invention in practice except as hereinafter claimed.

Having shown and described my invention, what I now claim as new and desire to secure by Letters Patent of the U. S. is:—

35

- 5 1. In a railway switch of the class described, in combination with the switch points of a railway track, double frogs at each point slideable with the switch points, locking members for said frogs, rock shafts removed from and connected to said frogs and locking members, and means to actuate either of said rock shafts and its connected frogs and locking members to open and close the selective switch points.
- 10 2. In a railway switch of the class described, in combination with the switch points of a railway track, a pair of slideable frogs on each side of the switch points, independent locking members for each pair of frogs, spaced rock shafts forward of said switch points and connected to the frogs and locking members, and means to actuate said frogs and locking members by either of said rock shafts to open and close the selective switch points.
- 15 3. In a railway switch of the class described in combination with the switch points of a railway track, horizontally slideable frogs on each side of the switch points, slideable locking members for each pair of frogs, spaced, transverse rock shafts connected to each pair of frogs and its slideable members, and means to actuate either of said

rock shafts whereby one pair of frogs will be locked to the switch points and one pair of frogs unlocked.

4. In a railway switch of the class described in combination with the switch points of a railway track, a pair of horizontally slideable frogs on each side of the switch points and independently slideable, locking members for each pair of frogs secured to the track, transverse rock shafts beneath the track and connected to each pair of frogs and locking members and means for actuating either of said rock shafts to lock one pair of frogs to the switch points and unlock the other pair.

40

5. In a railway switch of the class described in combination with the switch points of a railway track, horizontally slideable frogs on each side of said switch points, U-shaped plates secured between the track, locking members slideable in said U-shaped plates for locking the said frogs, transverse rock shafts secured beneath the track and provided with cables and connecting rods for actuating said frogs and locking members from the rock shafts and means to lock the respective frogs from opposite sides of the track.

50

In testimony whereof, I affix my signature hereto.

55

JAMES P. SCARTSARIS.
